UNITED STATES PATENT OFFICE.

KARL R. PETERS, OF PHILADELPHIA, PENNSYLVANIA.

SHIM FOR SPRINGS AND THE LIKE.

1,417,279.

Specification of Letters Patent. Patented May 23, 1922.

Application filed December 2, 1921. Serial No. 519,347.

To all whom it may concern:

Be it known that I, KARL R. PETERS, a citizen of the United States, residing at Philadelphia, in the county of Philadelphia and State of Pennsylvania, have invented certain new and useful Improvements in a Shim for Springs and the like, of which the following is a specification.

My invention relates to improvements in a friction reducing shim for springs, particularly plate springs for vehicles.

The object of my invention is to provide a sheet of metal which may be placed between the plates of springs for reducing the friction between the plates, and also preventing the surface of the plates of the spring from rusting; a further object of my invention is to provide a sheet or strip of material which will have sufficient stiffness and resilience to retain its shape and position between the spring plates; a further object of my invention is to provide an oil-less friction reducing device for springs which will not lose its anti-friction qualities due to constant wear, and which will not require any attention after it is installed.

In carrying out my invention, I provide a friction reducing substance consisting of a soft metal having graphite pressed into its texture, and I further provide a stiffening plate or stay sheet, of harder metal, for carrying the said soft metal friction reducing substance. The stay sheet of harder metal gives sufficient rigidity to the complete sheet or strip to insure the latter against buckling or twisting, due to the action of the spring plates, which tends to displace anything placed between the plates. A soft metal sheet of anti-friction material will be quickly forced out from between the spring plates or crushed by the pressure of said plates. After much experimenting it has been found that a sheet of relatively rigid material combined with a coating of softer material, having anti-friction qualities, and made in accordance with my invention, will give the results desired.

Referring to the accompanying drawing; Fig. 1 is a perspective view of a portion of a plate spring having my improved friction reducing strips, or shims, interposed between the plates; Fig. 2, is a perspective view of the shim or strip of material showing the different parts thereof; and Fig. 3 is a sectional view of the strip of material, drawn on an enlarged scale.

In the drawings in which like reference characters refer to like parts, 1 represents a strip or sheet of material adapted to be placed between the plates 2 of springs such as are now in general use upon vehicles.

The strip or sheet of material 1 consists of a central sheet 3 of thin metal, which is relatively hard and sufficiently resilient to retain its shape. The central sheet 3 is coated with layers 4 and 5 of soft metal, such as Babbitt metal.

The central sheet 3 is preferably made of an alloy consisting of copper and tin. Bell-metal has been found to give satisfactory results. These alloys will readily unite with the softer metal by fusion to form the coating surfaces upon the central sheet.

The soft metal coatings 4 and 5 are applied, by fusion, to the surfaces of the central sheet 3. Graphite 6 is then pressed into the layers 4 and 5 of the soft metal, by passing the sheet of combined materials between pressure rolls, in the presence of flake graphite.

The soft metal coating upon the central sheet 3 will be impregnated with the graphite, and thus form a friction reducing material adapted for the purposes herein set forth.

The material is made in sheets which are cut into strips of various widths to suit different sizes of springs. The strips may be rolled into a compact bundle and sold in this form. It may be readily cut into the proper lengths to suit the springs which are to be equipped with the shims or strips of friction reducing material.

Having thus described my invention I claim and desire to secure by Letters Patent:

1. A friction reducing shim adapted to be inserted between plates of springs and the like, consisting of a soft metal having anti-friction qualities, and a stay sheet of relatively harder material upon which the said softer metal is applied.

2. A friction reducing shim adapted to be inserted between plates of springs and the like, comprising a sheet of soft metal impregnated with graphite.

3. A friction reducing shim adapted to be inserted between plates of springs and the like, comprising a stay sheet of relatively hard and resilient metal, a coating of relatively soft metal upon opposite faces of said sheet, and said soft metal coating impregnated with graphite.

4. A friction reducing device for plate springs and the like, comprising a sheet of relatively hard and resilient metal, layers of babbitt metal applied to the opposite surfaces of said sheet, and graphite impregnated into the babbitt metal.

5. A friction reducing device for plate springs and the like, comprising a sheet of bell metal, babbitt metal coated upon opposite surfaces of the sheet of bell metal and graphite pressed into the babbitt metal.

6. A spring having in combination a friction reducing shim between the plates of the

spring, said shim consisting of a central sheet of hard resilient material, and layers of relatively softer material having a friction reducing substance embodied therein applied to the surfaces of the said central sheet.

7. The method of forming a friction reducing shim, consisting of coating a hard resilient sheet of metal with a relatively softer metal and pressing graphite into the surface of the said coating metal.

In testimony whereof I affix my signature.

KARL R. PETERS.
